[57] **CLAIM**

The ornamental design for the presser foot for sewing machine, as shown and described.

DESCRIPTION

FIG. 1 is a front perspective view of the presser foot for sewing machine showing my new design;
FIG. 2 is a front elevation view thereof;
FIG. 3 is a rear elevation view thereof;
FIG. 4 is a right elevation view thereof; and,
FIG. 5 is a left elevation view thereof.

The broken lines are for illustrative purposes only, and forms no part of the claimed design.
